UNITED STATES PATENT OFFICE.

HARRY B. JOHNSTON, OF SEATTLE, WASHINGTON.

PISTON AND PISTON RING.

1,418,931.

Specification of Letters Patent. Patented June 6, 1922.

Application filed April 15, 1922. Serial No. 552,944.

To all whom it may concern:

Be it known that I, HARRY B. JOHNSTON, residing at Seattle, county of King, State of Washington, a citizen of the United States,

5 have invented certain new and useful Improvements in Pistons and Piston Rings, of which the following is a specification.

This invention relates to pistons and piston rings and has particular relation to pistons and rings for use in cylinders where it is necessary to maintain a tight seal between the piston and cylinder wall.

The primary object of my invention is the provision of an improved piston having a groove with an inclined wall, a ring in the groove and an improved method of permitting the pressure, at the end of the cylinder, to come into contact with the ring in a manner to facilitate the proper seating of the 20 ring with the cylinder wall.

Another object of my invention is the provision of an improved hollow piston having a groove with an inclined wall, a ring in the groove and having outwardly 25 divergent opposite walls, the piston being provided with a communication between the interior of the piston and one side of the ring, the piston having a cylindrical cylinder bearing surface on each side of the ring.

30 Another object of my invention is the production of a piston having means for preventing over oiling in, for instance, an internal combustion motor.

Still another object is the provision of an 35 improved ring joint.

Other and further objects will be apparent as the structure is understood.

Referring to the drawing wherein preferred forms of my invention are illustrated,

Figure 1 is a section of a piston illustrating my invention.

Figure 2 is an elevation of the embodiment of my invention illustrated in Fig. 1.

45 Figure 3 is a sectional view of a modified form of Fig. 1.

Figure 4 is an elevation of the form shown in Fig. 3.

Fig. 5 is a modified form of piston illustrating the adaptation of the ring and groove shown in Fig. 1, to both ends of the piston.

Fig. 6 is a broken view of the ring.

Referring to Figs. 1 and 2, 10 designates a piston having a head 11. The piston is provided with a groove 13 having an inclined wall 14 on the side opposite the adjacent

end of the piston. A split ring 15 is provided for the groove and has an inclined surface 16 which corresponds to and contacts with the inclined wall 14 of the groove 13. 60 The head 11 is cut away adjacent its outer periphery in such a manner as to permit the pressure at the end of the piston to reach the surface 17 of the ring 15. The oppositely disposed surfaces 17 and 16 are outwardly divergent relative to each other. The ring fits the groove in such a manner that preferably when compressed to its inward position, it is at or slightly within the periphery of the piston. 70

Intermediate the ends of the piston and shown in Figures 1 and 2 on the opposite side of the wrist pin hole 18, from the groove 13, is a groove 19 having a split ring 20 for cooperation therewith. The groove 19 is provided with an inclined wall 21 which is oppositely inclined relative to the inclined wall 14 of the groove 13. 75

The ring 20 is preferably fitted to its groove 19 in such a manner that when compressed, its periphery will be at or slightly within the periphery of the piston. 80

The ring has an inclined surface 22 in contact with the inclined wall 21 of the groove. 85

Communicating with the surface 23 of the ring are holes 24 which are bored through the piston wall into and communicating with the interior of the piston. A suitably shaped channel 25 is provided to permit the surface of the ring to be affected by the pressure within the open end of the piston, through the openings 23 and throughout the periphery of the ring. 90

The ring and groove construction shown 95 at the bottom of Figure 1 is particularly advantageous in an engine where it is desirable to have the skirt portion 26 of the piston extend out beyond the cylinder bore at one end of the stroke while obviously the ring at the end of the stroke must extend at least a portion within the bore. 100

The action of the ring 15 in the groove 13 is as follows:—

The pressure at the end of the piston 105 comes into contact with the surface 17 of the ring 15. This pressure downward presses the ring along the inclined surface 14, outwardly against the cylinder wall. This action causes a tight seal to be effected 110 between the piston and ring through contact between the inclined surfaces 14 and

16. At the same time, a tight seal is effected between the ring and cylinder wall, all excess oil being forced along with the movement of the ring. While in the ordinary construction, the tendency of the rings is to collapse in the construction shown in the drawing, the tendency is always to expand the ring when the pressure comes from the right direction.
- 10 The operation of the ring 20 in its groove 19, when applied, for instance, to an internal combustion motor, is as follows:—
- 15 On the power stroke, the friction between the ring 20 and the cylinder wall, caused by the spring tension of the ring, causes the ring to act as a check valve, because of the inclined surfaces, and effectively holds the ring against the cylinder wall. This tends to scrape any oil, which may be present on 20 the cylinder wall, into the channel 25 and into the openings 24. The oil drains along the inside wall of the piston to the edge 27 from where it drops into the crank case. At the bottom of the piston is a groove 28 25 which also aids in preventing overoiling of the pistons.

During the suction stroke, the piston is moving downward, atmospheric pressure enters through the openings 24 and presses 30 upon the ring 20 causing it to have a tendency to move outwardly along the inclined seat and effectively seat against the cylinder wall. Any oil which might be present on the wall of the cylinder is scraped downward, it being drained out from the holes 24 or at the outer lower edge of the piston.

In Figures 3 and 4 is illustrated a form 40 of the invention wherein the piston 10^a is provided with a head 11^a, a groove 13^a, the groove having an inclined wall 14^a. A ring 15^a is provided in the groove 13^a and has an inclined surface 16^a and an opposite surface 17^a outwardly divergent with relation to the surface 16^a. The piston is provided 45 with a wrist pin hole 18^a. A groove 19^a is provided on the same side of the wrist pin hole 18^a as the groove 13^a. This groove 19^a is provided with a ring 20^a having an inclined surface 22^a engaging an inclined 50 wall 21^a of the groove. An opposite surface 23^a is provided, being outwardly divergent with relation to the inclined surface 22^a in contact with the wall 21^a of the groove. Adjacent the groove 19^a is a channel 25^a having openings 24^a communicating with the interior of the piston. The skirt

26^a is provided with a groove 28^a between a sharp edge 27^a and a similar edge at the outer edge of the piston.

The parts 10^a to 28^a inclusive correspond 60 to the parts 10 to 28, respectively, of Figures 1 and 2.

In the form shown in Figure 5, a piston 10^b is provided with two grooves having rings 20^b on opposite sides of the web 11^b. 65 The grooves are provided with oppositely disposed inclined walls 21^b for cooperation with corresponding faces 22^b on the respective rings. The ring grooves have adjacent channels 25^b which are provided with 70 openings 24^b which extend through the wall to the interior of the piston. In the form shown in Fig. 5, a piston rod 30 is secured in the web 10^b by the nut 31 on the screw threaded end 32 of the rod.

In Figure 6, is shown a ring partly broken away and showing the step S-joint 31 which is shown as a preferred form of step joint as its construction is one which ensures maximum strength.

The actions of the rings 20^a and 20^b are similar to the action of the ring 20 and will not be repeated in full.

While I have described embodiments of my invention in detail, I desire to have it 85 understood that I do not limit myself to the exact structures shown and that modifications and changes may be made without departing from the spirit of my invention and within the scope of the appended claims. 90

Having described my invention, what I claim is:—

1. A hollow piston having a groove, the groove having an inclined wall, the wall of the piston being provided with a hole to 95 communicate with the groove to permit the pressure of the interior of the piston to communicate with the groove, a metallic ring in the groove, the ring having an inclined surface to cooperate with the inclined wall 100 of the groove.

2. A hollow piston having a ring groove, the groove having an inclined wall, a ring in the groove and having an inclined surface cooperating with the inclined wall of the 105 groove, the piston having a channel adjacent the ring groove and openings from the channel to the interior of the piston.

In testimony whereof I hereunto affix my signature.

HARRY B. JOHNSTON.
